UNITED STATES PATENT OFFICE.

WILLIAM J. MORTON, OF ST. LOUIS, MISSOURI, ASSIGNOR, BY MESNE ASSIGNMENTS, TO
McBEE BINDER COMPANY, OF ATHENS, OHIO, A CORPORATION OF OHIO.

PERFORATING AND BINDING MACHINE FOR LETTER-SHEETS.

1,265,238.

Specification of Letters Patent.

Patented May 7, 1918.

Application filed June 30, 1914. Serial No. 848,187.

To all whom it may concern:

Be it known that I, WILLIAM J. MORTON, a citizen of the United States, residing at city of St. Louis, State of Missouri, have invented a certain new and useful Improvement in Perforating and Binding Machines for Letter-Sheets, of which the following is a full, clear, and exact description, such as will enable others skilled in the art to which it appertains to make and use the same, reference being had to the accompanying drawings, forming part of this specification, in which,—

Figure 1 is a front elevational view of a perforating and binding machine of my improved construction.

Fig. 2 is a rear elevational view of the machine.

Fig. 3 is a top plan view of the machine for letter sheets with portions thereof broken away and in section in order to more clearly illustrate certain mechanism of the machine.

Fig. 4 is a vertical section taken approximately on the line 4—4 of Fig. 3, and showing the drills forming a part of the machine in lowered position.

Fig. 5 is an enlarged horizontal section taken approximately on the line 5—5 of Fig. 4.

Fig. 6 is a detail view of one of the slotted cams or eccentrics utilized in raising and lowering the drills.

Fig. 7 is a plan view of a portion of the assembling box forming a part of the machine and showing the handle utilized for locking a movable portion of said box.

My invention relates to new and useful improvements in machines utilized for perforating and binding paper or other sheets, such for instance, as way-bills, checks and the like, the principal object of my invention being to generally simplify and improve upon the existing machines of the type to which my present invention pertains.

Further objects of my invention are, to provide a simple container or assembling box for the sheets, a portion of which box is hinged so that it may be readily swung downward into an out-of-the-way position while the perforated sheets are being engaged by parts of the binder; to provide simple means for clamping and rigidly holding all of the sheets while the same are being perforated and engaged by the binder; to

provide simple means for simultaneously driving all of the drills or implements utilized for perforating the sheets; to provide simple means for simultaneously raising and lowering all of the drills, and to provide a machine of the character specified which is comparatively simple in construction and operation, inexpensive in manufacture, effective and reliable in use and possessing the capacity for effecting a material saving of time and labor in the operations incident to the perforating and binding of sheets.

With the foregoing and other objects in view, my invention consists in certain novel features of construction and arrangement of parts, hereinafter more fully described and claimed.

Referring by numerals to the accompanying drawings, 10 designates the base of the machine which is preferably in the form of a table, and projecting forwardly from the front corners thereof are extensions 11 which serve as supports for the lower ends of upright frames 12.

Hinged to the front edge of the table 10 between the extensions 11 is a plate 13 which, when in horizontal position, occupies the same plane with the table 10, and formed integral with or fixed to the front edge of this plate 13 is a vertical plate or wall 14.

The parts 13 and 14 form a member which is substantially L-shape in cross section and which forms the front wall and forward portion of the bottom of the assembling box or sheet container.

Formed through the plate 13 and near the wall 14 is a series of apertures 15 which are adapted to accommodate drills forming a part of my improved machine, and herein-after more fully described.

Pivotedly mounted on the underside of the table 10 immediately to the rear of the central portion of the plate 13 is a lever 16 provided on its forward end with a handle 17, and formed on top of said lever is a rib or lug 18 which is adapted to engage beneath a rib 19 which latter is formed on the underside of the plate 13.

When the lever 16 is swung around to one side as shown by dotted lines in Fig. 7, the L-shaped member comprising the parts 13 and 14 swings downward by gravity into the position shown by dotted lines in Fig. 4, thereby exposing the forward portions of the sheets within the assembling box or con-

tainer, and thus permitting the application of a suitable temporary or permanent binder to said sheets (not shown).

When the lever 16 is swung around in position at right angles to the plane occupied by the L-shaped member forming the front of the assembling box as shown by solid lines in Figs. 4 and 7, the lug 18 engages beneath the rib 19, thereby locking the L-shaped member in position as shown by solid lines in Fig. 4.

Formed in the top of the table 10 and slightly to the rear of the front edge thereof, is a longitudinally extending groove 20 which is substantially of inverted T-shape in cross section and arranged to slide in said groove are the heads of upwardly projecting screws 21 which carry vertically disposed side plates 22. These screws receive winged nuts 23, whereby said screws may be tightened to lock plates 22 in their adjusted positions. These plates form the sides of the assembling box or container of the machine, and by loosening the winged nuts 23, said plates can be readily adjusted toward and away from each other as may be required in use.

Formed integral with or fixed to the uprights 12 is a vertically disposed web or plate 24 and formed integral therewith is a series of vertically disposed sleeves 25. Positioned on top of the web 24 and sleeves 25 is a suitable housing 26 in which is located the train of gearing which operates the drills forming a part of the machine.

Fitting snugly within each sleeve 25 is a sleeve 27, the same being provided with a vertically disposed row of teeth to form a rack 28, and formed in said sleeve is a vertically disposed groove 29 in which engages the inner end of a screw 30, which latter is seated in the lower portion of the corresponding sleeve 25. Thus each sleeve 27 is held to move vertically within its sleeve 25. Mounted for rotation within each sleeve 27 is a spindle 31, the same being provided with a collar 32 which normally rests on top of the sleeve 27 and formed in the upper portion of this spindle is a vertically disposed groove 33.

Formed on or fixed to the lower end of each spindle is a socket 34 in which is removably seated the upper end of an ordinary twist drill 35. A suitable ball-bearing 36 is arranged between the upper portion of the socket 34, and the lower end of the sleeve 27.

Journalized in suitable bearings formed on the sleeves 25 is a horizontally disposed shaft 37 provided on its left hand end with a hand wheel 38 and carried by said shaft are pinions 39 which extend through suitable apertures formed in the sleeves 25 and engage the racks 28 on the sleeves 27. This construction provides means for simultaneously and uniformly raising and lowering

the spindles 31 and the drills carried thereby.

Arranged on the spindles 31 and within the housing 26 are pinions 40, the same being provided with keys 41 which engage in the corresponding grooves 33 in said spindles and interposed between these pinions 40 are comparatively small pinions 42 which serve to transmit proper rotary motion to said pinions 40.

The pinion 42 at the right hand end of the train of gearing is carried by the upper end of a vertically disposed shaft 43 which operates in a suitable bearing 44 at the right hand end of the housing 26, and fixed on the lower end of this shaft is a beveled pinion 45.

Meshing with this last mentioned pinion is a beveled pinion 46 which is carried by the shaft of a motor 47, the latter being mounted upon a suitable bracket on the right hand one of the uprights 12.

The train of gearing just described provides means for correspondingly and uniformly rotating all of the drill carrying spindles 31.

Formed on the inner faces of the lower portions of the uprights 12 are comparatively short vertically disposed ribs 48, and arranged to slide freely thereupon are the ends of a horizontally disposed clamping bar 49.

Journalized in suitable bearings on the uprights 12 above the ribs 48 is a shaft 50 on the left hand end of which is fixed a hand wheel 51. Rigidly fixed on this shaft is a pair of segmental plates 52 in each of which is formed a curved slot 53, the same being eccentric with respect to the shaft 50.

Formed on or fixed to the bar 49 are pairs of ears 54 and seated therein are pins 55 which pass through the eccentric slots 53. The mechanism just described provides means for raising and lowering the clamping bar 49 and locking the same when it is moved downward to clamp a pile of sheets in the assembling box.

The operation of my improved machine is as follows:

The hinged member comprising the plate 13 and wall 14 is swung upward to the position shown in Fig. 4, said part being locked in its position by means of the lever 16. The sheets are now piled on the table 10 and the plate 13 with their edges at one side against the plate 14.

It will be understood that the plates 22 which form the ends of the assembling box can be adjusted toward or away from each other to correspond with the length of the sheets placed in the machine.

When the pile of sheets has been completed and it is desired to perforate the same in order that they may be bound, an operator manipulates hand wheel 51, thereby swing-

ing the plates 52 downward and consequently moving the clamping bar 49 downward by reason of the engagement of the pins 55 in the eccentric slots 53, and this 5 movement causes the bar 49 to engage and bear with considerable pressure on top of the pile of sheets.

The motor 47 is now operated, and as a result, rotary motion is imparted to shaft 43 10 and by reason of the train of gearing comprising the pinions 40 and 42, within the housing 26, all of the spindles 31 are correspondingly and uniformly driven.

It will be understood that all of the sleeves 15 27 carrying the drill spindles 31 are normally at their upper limit of movement, and thus the points of the drills are normally positioned in a plane slightly above the plane occupied by the top of the plate 14.

20 The operator now manipulates hand wheel 38 to rotate shaft 37, thereby causing the pinions 39 to engage the racks 28, thus moving the sleeves 27 downward, and as a result all of the drill carrying spindles 31 are 25 likewise moved downward during which time said drill spindles are being rotated by the action of the gearing within the housing 26. Thus, the drills 35 carried by the lower ends of the drill spindles are caused to move 30 downward through the pile of sheets positioned on the table, and as a result, a series of apertures are quickly formed through said pile of sheets in one edge thereof.

As the lower ends of the drills reach their 35 lower limit of movement, they pass through the apertures 15 in the plate 13. As soon as the drilling operation has been completed, the operator manipulates hand wheel 38 to bring about a reverse or elevating movement 40 of the sleeves 27, and the drill spindles carried thereby, and when the drills have been wholly withdrawn from the pile of sheets, the operator swings the lever 16 to one side, thereby permitting the front portion of the 45 assembling box to swing downward as shown by dotted lines in Fig. 4, and the prongs or binding members of a suitable temporary or permanent binder (not shown) can now be inserted through the apertures, thereby 50 easily and quickly binding the entire pile of sheets. As soon as this operation has been completed, the operator manipulates the hand wheel 51 to elevate the clamping bar 49 and the bound sheets can now be removed 55 from the machine.

A perforating and binding machine of my improved construction is comparatively simple, can be easily operated and provides simple means whereby a series of apertures 60 can be readily formed in a pile of sheets of paper or the like.

It will be readily understood that minor changes in the size, form and construction of the various parts of my improved perforating and binding machine can be made and 65 substituted for those herein shown and described, without departing from the spirit of my invention, the scope of which is set forth in the appended claims.

I claim:

1. In a machine of the class described, the combination with a support for sheets to be perforated, of a frame above said support, a series of vertically disposed bearings formed on said frame, a housing on said frame 70 above said bearings, sleeves arranged for sliding movement in said bearings, each sleeve being provided with a vertically disposed groove, a set screw seated in each bearing, the inner end of which set screw engages in the groove of the corresponding sleeve, each sleeve being provided with a row of teeth, spindles loosely mounted in said sleeves, the upper portions of all of which spindles extend upward through the hous- 75 ing, a series of connected pinions arranged within the housing and splined upon the spindles for operating the same, drills carried by the lower ends of said spindles, a horizontally disposed shaft mounted for ro- 80 tation on the frame in front of the bearings, and pinions carried by said shaft, which pinions mesh with the teeth on the sleeves.

2. In a machine of the class described, a support for sheets to be perforated, a frame 90 above said support, a series of vertically disposed bearings formed on said frame, a housing on said frame above the bearings, sleeves arranged for sliding movement in said bearings, each sleeve being provided 95 with a vertically disposed groove, a set screw seated in each bearing, the inner end of which set screw engages in the groove of the corresponding sleeve, spindles loosely mounted in said sleeves, the upper portions 100 of all of which spindles extend upward through the housing, a series of connected pinions arranged within the housing and splined upon the spindles for operating the 105 same, drills carried by the lower ends of 110 said spindles, means for simultaneously raising or lowering all of the sleeves and parts carried thereby, and means for driving the series of connected pinions.

In testimony whereof I hereunto affix my 115 signature in the presence of two witnesses, this 25th day of June, 1914.

WILLIAM J. MORTON.

Witnesses:

M. P. SMITH,
